UNITED STATES PATENT OFFICE.

HENRY L. PITMAN, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,417,685.

Specification of Letters Patent. Patented May 30, 1922.

Application filed May 15, 1919. Serial No. 297,274.

To all whom it may concern:

Be it known that I, HENRY L. PITMAN, a citizen of the United States, residing in Elizabeth, in the county of Union and State 5 of New Jersey, have invented certain new and useful Improvements in Combined Typewriting and Computing Machines, of which the following is a specification.

This invention relates to combined typewriting and computing machines, and is 10 herein shown as applied to the kind shown in my co-pending application, No. 186,098, filed August 14, 1917, (now Patent No. 1,345,460, dated July 6, 1920) in which a 15 column-computor unit and a cross-computer unit are used; each unit comprising two elements, namely, a totalizer and a master wheel or actuator, one of said elements traveling relatively to the other. In this kind of machine, there is also provided a computer carriage or sub-carriage upon which the traveling element of the cross-computer unit may 20 be supported, so that it may travel intermittently with the typewriter carriage.

25 The invention may be used in connection with parts disclosed in my co-pending application, No. 282,277, filed March 13, 1919, in which the computation is performed by means actuatable by a motor-drive; the 30 motor-drive being renderable active by a motor-release under the control of numeral type keys; and the motor-release having a connection extending therefrom, to render effective a locking device for the escapement 35 mechanism of the typewriter carriage.

An object of the present invention is to render the numeral keys ineffective when the typewriter carriage reaches the punctuation positions between the various groups 40 in a column of numbers, while the carriage is passing through a computing zone. This may be done by locking the connection extending from the motor-release, when the typewriter carriage reaches the punctuation 45 position, thus locking the numeral keys against actuation.

This locking of the keys may be accomplished by means on the typewriter carriage or means on the sub-carriage. The column-totalizers, of which there may be one or more 50 arranged to travel with the typewriter carriage, may be adjusted to positions which correspond to various columns on a work-

sheet, which may be carried by the typewriter carriage. Each column-totalizer is 55 provided with a series of cams or tappets at punctuation positions thereof, which, as the carriage passes through a computing zone, engage with a cam on a lever to swing it about its pivot to actuate a rock-shaft 60 through the medium of an arm on said rock-shaft; the latter having connected thereto means which extends to the back of the machine where it is connected to actuate a locking pawl to bring it into locking relation 65 with a link of the connection extending from the motor-release, to lock the numeral keys.

It is sometimes desired, when typing numbers in a column, to run the numbers into the cross-totalizer only. In such a case the columnar position of the carriage is not provided with a column-totalizer. It is further desirable, however, to lock the keys when the punctuation positions in such a column are reached. To do this, the cross-computer 75 carriage is provided with a series of tappets, which engage with an arm, extending from the rock shaft, having the key-locking means connected thereto, so that the latter may be 80 actuated in the various punctuation positions, as the cross-totalizer passes through the computing zone with the typewriter carriage.

The invention may also be used with mechanism shown in my co-pending application, 85 No. 212,213, filed January 17, 1918 (now Patent No. 1,386,653, dated August 9, 1921), in which there is shown means to reconnect the cross-computer carriage with the typewriter carriage by means connected with a back-spacer key. Provision is also made in said application to lock the numeral keys in case the operative backs the typewriter carriage into the computing zone without the aid of the back-spacer key, thus compelling 90 the operative to actuate the back-spacer key, to assure the reconnection of the cross-computer carriage and the repositioning of the cross-totalizer relatively to its actuator, before the actuation of a numeral key.

In the present invention, means is provided to lock the numeral keys when the carriage is backed into a computing zone, as above described. For this purpose, I have found it advantageous to utilize part of the 105 above-described locking mechanism, includ-

ing the pawl which engages with the link extending from the release for the power-drive.

In the present invention, the releasing means for the power-drive includes a universal element or bar with which all of the numeral keys may be associated; the universal bar being so arranged that a slight depression of any one of the numeral keys 5 may actuate said universal bar and release the power-drive. Just prior to the release of the power-drive, the actuated key becomes connected with the universal bar, and the latter is then actuated by the power-drive to assist in actuating the type-bar and to actuate the computing mechanism to run the number into the totalizer. If two numeral type keys should accidentally be actuated and become connected with the universal bar, there would be a collision 10 between the type-bars of the actuated keys as they approached the printing point. Furthermore, this would have an undesirable result on the computing mechanism.

25 Provision is made to prevent the simultaneous depression of two numeral keys, and consequently prevent the possibility of two keys being actuated by the motor-drive at the same time. For this purpose, there is 30 provided key-locking means which may be like that disclosed in my co-pending application, No. 181,460, filed July 19, 1917 (now Patent No. 1,349,386, dated August 10, 1920). Each numeral key is provided with 35 a pendant having an intruding wedge thereon, which may enter between two pivoted pawls. Each wedge is provided with two pawls, all of the pawls forming a group supported between two studs with sufficient 40 play between the studs to permit the intrusion of only one cam at a time.

Provision is further made to prevent the release of the typewriter carriage by a tabulator key while a computing action is taking place, the effect of which would not only cause an incorrect result in the totalizer, but would also cause a collision between co-operating parts of the computing mechanism. To do this, there is provided an intruding 50 member which is actuatable by any one of the tabulator keys to engage between two of the pawls of the group associated with the intruding cams of the numeral keys. If a numeral key is active, the intruding member 55 cannot enter between the pawls, consequently locking the tabulator keys against actuation, and preventing the release of the carriage. With this key-locking means, it is also impossible to actuate a numeral key to 60 release the power drive and actuate the computing mechanism while a tabulator key is active.

The computing mechanism may be rendered ineffective by a non-compute key connected to render the motor-release ineffec-

tive. This may be done without having any effect on the means which locks the numeral keys at punctuation positions of the carriage, and which is also associated with the motor-release.

70

Other features and advantages will hereinafter appear.

In the accompanying drawings,

Figure 1 is a side elevation of the machine as viewed from the right-hand side, 75 certain parts being broken away and parts being omitted for the sake of clearness.

Figure 2 is a skeleton perspective view of the machine as seen from the upper left-hand corner, and shows the numeral key-locking mechanism which may be rendered effective by either the column-totalizers or the cross-totalizer, one of the column-totalizers and the cross-totalizer being shown as passing through the computing zone with 80 85 the typewriter carriage.

Figure 3 is a perspective view of some of the numeral-key-locking means for preventing the simultaneous actuation of two keys.

Figure 4 is a diagrammatic perspective 90 view as seen from the upper right-hand corner, showing the release for the power-drive and the key-lock associated therewith.

Figure 5 is a sectional view showing the valuating and actuating mechanism, the 95 parts being shown in normal positions.

Figure 6 is a perspective view of the means for rendering the key-locking mechanism effective when the typewriter carriage is backed into the computing zone without the 100 aid of the back-spacer key.

Figure 7 is a detail view of the key-locking mechanism, and shows the same rendered effective by one of the totalizers.

Figure 8 is a similar view, but shows the 105 key-locking mechanism rendered effective by the mechanism shown in Figure 6.

Numerical type keys 10 and alphabet type keys 11 swing key levers 12 about their fulcrum 13 against the tension of return springs 110 14 to rock bell-crank 15 about their common fulcrum 16; the upper ends of said bell-crank 15 being effective to swing type bars 17 upwardly and rearwardly about their fulcrum 18 to cause types 19, adapted to 115 strike the platen at a common printing point, to print against a work-sheet (not shown), which may be carried by a cylindrical platen 20 rotatable in a platen frame 21 supported on a carriage 22 which may travel 120 back and forth on a front rail 23 and a rear rail 24. The carriage 22 is constantly urged from right to left of the machine by means of a spring drum 25 connected thereto by a strap 26. The carriage 22 is permitted to 125 move in this direction, during typing operations of the type bars 17, by means of escapement devices including a universal bar 27 forming part of a floating frame 28, which is moved rearwardly during the lat- 130

ter part of the upward strokes of the type bars by heels 30 which engage the universal bar 27. The frame 28 is guided and carried at its rear end by a pivoted frame 31 comprising a rock shaft 32. The floating frame has therein a cross-bar 33 which engages with a dog rocker 34 to swing the upper end thereof rearwardly about its pivot 35 to move a loose dog 36, carried by said dog rocker, out of engagement with one of the teeth of an escapement wheel 37, and bring a fixed dog 38 into the path of the disengaged tooth. The loose dog 36, after it becomes disconnected from the tooth, is swung about its pivot 40 and towards the left of the machine by means of the usual spring (not shown). The escapement wheel 37 at this time is held by the fixed dog 38. Upon the return movement of the floating frame, comprising the universal bar 27, which is caused by the usual return spring 41, the loose dog enters the space between the previously-engaged tooth and the next tooth, and the escapement wheel becomes released from the fixed dog 38, which is rotated by means of the spring drum through the medium of a pivoted feed-rack 42 on the typewriter carriage, which rotates a pinion 43 having the usual one-way connection (not shown) with the escapement wheel 37. During this movement, the next tooth of the escapement wheel engages the loose dog 36 to swing it about its pivot 40 until it is finally arrested by a fixed stop 44 at the upper end of the dog rocker, the carriage having thus been moved through one letter-space distance.

The computing mechanism may comprise a column-computing unit 45, having an actuator 46 carried by the main frame 47, and one or more column-totalizers 48 adjustably mounted (at positions corresponding to the columns on the work sheet) on a bar 50. The bar 50 is arranged to travel on a fixed guide rail 51, and with the typewriter carriage, connection being had between the typewriter carriage and the bar 50 by one or more arms 52. Each totalizer may comprise a plurality of dial wheels 53 arranged in denominational order, side by side, and meshing with intermediate computing wheels 54, the latter being brought seriatim into effective relation with a master wheel 55, secured to a shaft 56 rotatably mounted in the actuator 46, during the letter-feeding movements of the typewriter carriage.

The master wheel 55 is herein shown as actuatable by power-driven mechanism which may be located in back of the main frame 47 and under the control of the numeral keys.

The power-driven mechanism may be like that disclosed in my said co-pending application No. 282,277, and comprises a power shaft 57, which may be rotated by a spring-

motor having a spring 58, which is connected to drive a gear wheel 60 meshing with a pinion 61 secured to said power shaft 57. The spring 58 may be wound automatically or, in other words, energy may be stored therein by means of an electric motor 59. The power shaft 57 is normally held by a pawl 62, which engages with a dog 63, connected with the power shaft 57. The power shaft 57 is provided with valuating cams 64 (Figure 5), one for each numeral key from "1" to "9," inclusive, which vary in size according to the values of the associated numeral keys. There is also provided a series of arms or interponents 65, one for each valuating cam, the interponents being normally out of co-operating relation with the cams, and slidably mounted on a valuating shaft 66, so that they may be brought individually and selectively into co-operative relation with their associated valuating cams:

When a numeral key 10 is actuated, the associated key lever 12 swings also a bell-crank 67 about a fulcrum rod 68, to push a link 70 rearwardly; said link 70 may be connected as shown in my said co-pending application No. 282,277, but is herein shown connected directly to a three-armed member 71, to actuate the latter, which is pivotally mounted on a rod 72 supported in a casing 73 for the power-driven mechanism (Figures 1 and 5). It will be understood that there is one three-armed member for each numeral key, and that each one is provided with a pin 74 to engage with one of a series of forked members 75, secured to a shaft 76; the forked members and the shaft 76 forming a universal bar which may be rocked by a slight depression of any numeral key to release the power shaft 57. The motor-release shaft 76 has secured near its right-hand end a bell-crank member 77, which has pivotally connected thereto an actuating member 78 having a tooth 80 thereon, to engage with a tooth 81 on the holding pawl 62, to swing the latter out of effective relation with the dog 63 on the power shaft 57, and thus release the latter so that it may be rotated by the spring motor 105 and run in the value of the actuated numeral key to the totalizer 48 in a manner presently to be described. After the power shaft has been released in this manner, a tail 82 on the holding dog 62 engages with said actuating member 78 to move the tooth 80 out of engagement with the tooth 81 on pawl 62, so that said pawl may be returned to its normal position by a spring 83, to be ready to arrest the power shaft 57, at the completion of a revolution thereof. Provision may also be made of a cam on shaft 57 to engage pawl 62 and insure its return to effective position.

The power shaft 57, after its release, is 130

4
effective to actuate the universal bar comprising the shaft 76 and the forked members 75, and thereby drive the actuated type-bar. For this purpose, there is provided a cam 84 secured to the power shaft 57, and engaging with a roller 85 on the bell-crank 77 secured to said motor-release shaft 76. At the instant of release of the power-shaft, the pin 74 of the three-armed member 71 engages in a slot 86 formed in the forked member 75, and consequently, when the cam 84 actuates the motor-release shaft 76, the forked member engages to actuate the three-armed member 71. The three-armed member when driven by the power shaft 57 is effective to pull an associated cam slide 87, (Figures 4 and 5), and by means of a cam slot 88 formed therein, into which projects a pin 90, it swings an intermediate member 91, the upper end of which engages between two walls 92 of the interponent 65 to move said interponent axially on the valuating shaft 66, and bring a roller 93 on said interponent into effective relation 25 with the associated valuating cam 64. The movements of the parts are so timed, that after the roller 93 has been moved over the valuating cam 64, the cam portion of the latter then engages with said roller to swing 30 the interponent 65. A finger 94 in said interponent engages with a standard 95 on the valuating shaft 66, to rock the latter until it is arrested by a stop 96 on the cam slide, with which a projection 97 on the 35 standard 95 engages; the stop 96 having previously been lowered into the path of said projection 97. It should be understood that there is one interponent 65 for each numeral key, and that the valuating shaft 40 66 may be rocked through different angular distances corresponding to the values of the numeral keys 10.

The various angular movements of the valuating shaft 66 may be transferred to 45 the master wheel by mechanism including a downwardly-projecting arm 98 secured near the right-hand side of the valuating shaft 66. The arm is adapted to draw a link 100 rearwardly, to rock a bell-crank 50 101 about a fulcrum rod 102 upon which it is pivotally supported. The bell-crank 101 when rocked, pulls downwardly on a link 103, which is connected to an arm 104, (Figures 1 and 4), fixed on a shaft 105 and 55 rocks the latter. The shaft 105 extends into the actuator 46, and has secured thereto at its inner end, a downwardly-extending arm 106 (Figure 4), which is effective to move a driving rack 107 forwardly by means 60 of a link 108; the driving rack having previously been moved into effective meshing relation with a pinion 110 by means hereinafter described. The pinion 110 is rigidly secured to a shaft 111, which has also a large 65 gear wheel 112 secured thereto; the latter

being adapted to mesh with either one of the pinions 113 and 114 for addition and subtraction; said pinions forming part of a state-setting mechanism which may be like that disclosed in my said co-pending application, No. 186,098. The pinion 114 is secured to the master-wheel shaft 56, so that the movements thereof may be transmitted to the master wheel 55, and then to the dial wheels 53, as hereinbefore described. 70 75

The driving rack 107 may be normally out of meshing relation with the pinion 110, and raised, during the early part of the rotation of the power shaft 57, to engage with the pinion 114, by a lifting cam 115 (Figure 80 4) secured to said power shaft 57; said cam being effective to rock a bell-crank 116 about a rod 117 upon which it is pivotally mounted, to pull rearwardly a link 118 connected to said bell-crank. The link 118 rocks 85 a bell-crank 120 about the fulcrum rod 102, to pull downwardly, a link 122 connected to an arm 123 extending from a shaft 124, to rock the latter in a clockwise direction. The shaft 124, has secured thereto a downwardly-extending arm 125, to which is connected a link 126, to rock a shaft 127 in a counter-clockwise direction by means of an arm 128 extending from said shaft. The shaft 127 has thereon a cam engaging with 90 a forked arm 130 to rock a shaft 131, to which said forked arm 130 is secured, in a clockwise direction. The rock shaft 131 extends into the actuator 46, and has secured thereon, at its inner end, a bell-crank 132, 100 to raise the driving rack 107, which is partly supported on said bell-crank by a headed stud 133, which engages in a slot 134 of said rack. A similar bell-crank 135 is pivotally mounted on the shaft 124, and is connected by a link 136 to move with the bell-crank 132 and to guide the rear part of the driving rack 107; said bell-crank being also provided with a stud 137 engaging in a slot 138 to support the rear part of the rack. 110 After the driving rack 107 has been raised into engagement with the associated pinion 110, the valuating shaft 66 is actuated to transfer the number to the dial wheel, as hereinbefore described. 115

After the number has been run into the totalizer, the driving rack 107 is lowered out of engagement with the pinion 110 prior to its return to normal position. For this purpose there is provided a rack-lowering 120 cam 140 secured to the power-shaft 57, which engages with the bell-crank 116 to swing it in a counter-clockwise direction, to restore the connected parts, including the bell-cranks 132, 135, to their normal positions, 125 thus disengaging the driving rack 107.

The driving rack 107, after it is disengaged from the pinion 110, may be restored to its normal position by means of a spring 141 coiled around the valuating shaft 66; 130

one end of the spring being secured to said shaft 66, and the other end being connected to an arm 142 pivotally mounted on said valuating shaft. There is also a cam 5 143 secured to the power shaft 57, which may assist in returning the rack to its normal position. The cam 143 is adapted to swing the arm 142 in a clockwise direction to cause a finger 144 on said arm to 10 engage with a stud 145 on the arm 98, and rock said valuating shaft 66 in a clockwise direction, to its normal position.

Mechanism is provided to prevent any 15 possibility of repeated typing of a number and feeding the typewriter carriage 22, without computing. This mechanism may be like that disclosed in my said co-pending application No. 282,277, and may include a locking pawl 146 pivoted at 147, on the 20 casing 73. The locking pawl 146 is normally held in an ineffective position against the tension of a spring 148 by means of a pivoted controlling member 150, connected by a link 151, to the bell-crank member 77 25 on the motor-release shaft 76. When the motor-release shaft is actuated, as hereinbefore described, by the depression of a numeral key 10, the link 151 is moved against the tension of a return spring 149 30 to swing the controlling member 150 away from the holding pawl, thus permitting the spring 148 to swing the holding pawl 146 in a counterclockwise direction and render it effective. The holding pawl is arrested 35 in its effective position against the periphery of a co-operating member 152. It will be understood that this happens during the early part of the depression of any one of the numeral keys 10. During the latter part 40 of the depression of a numeral key, the heel 30, of the associated type bar 17, engages with the universal bar 27, to move the latter rearwardly to release the loose dog 36, and bring the fixed dog 38 into the path of the 45 teeth of the escapement wheel 37. The pivoted frame 31 is also actuated at this time, the rock shaft 32 thereof being provided with a downwardly-projecting arm 153, which is swung in a clockwise direction 50 and, by means of a pin-and-slot connection 154, actuates an arm 155, secured to a shaft 156, to rock the latter in a counter-clockwise direction. The rock-shaft 156 has secured thereto, near its right-hand end, an upwardly-projecting arm 157, which pulls a link 158 forwardly to swing the co-operating member 152 about its pivot 160, thus 55 permitting the locking pawl 146 to drop into a notch 161, formed in the co-operating member 152, thereby locking said co-operating member and the connected parts, including the dog rocker 34, in their actuated positions to hold the carriage against movement. The parts are so timed that the co- 60 operating member 152 becomes released from 65

the holding pawl 146, by the controlling member 150, after the parts have returned to a position from which the power shaft 57 may again be released by another actuation of the numeral key 10. To insure this condition, the tooth 80 on the actuating member 78 moves into effective relation with the tooth 81 on the holding pawl 62, immediately prior to the withdrawal of the locking pawl 146, from the notch 161, by 70 the return movement of the controlling member 150, or, in other words, immediately prior to the releasing of the locking pawl 146.

Provision is made to insure spaces for 80 punctuation between the groups of numbers, which spaces may be left blank, or in which suitable punctuation marks may be typed. Further provision is made to prevent the typing of numbers in these punctuation 85 spaces or positions. To accomplish the foregoing, the numeral keys are rendered ineffective when the punctuation spaces are reached. To do this it has been found advantageous to lock the link 151 which renders 90 the locking pawl 146 effective and which is connected to the motor-release shaft 76. For this purpose there may be used a pawl 162, which may engage with said link 151, thereby locking the motor-releasing mechanism, 95 and consequently preventing the actuation of the numeral keys and the computing mechanism. To cause the pawl 162 to engage with the link 151, each totalizer 48 may be provided with tappets or cams 163 (Figure 2) 100 at the punctuation positions of the totalizer. After typing the last number of each group, or in other words, the number preceding a punctuation position, one of the tappets 163 engages with a cam 164, to swing a horizontally-disposed lever 165 about its pivot 166; said horizontally-disposed lever being located at the back of the actuator 46, and extending toward the right-hand side thereof, where the free end of said lever engages 110 with an upwardly-projecting arm 167, secured to a shaft 168, to rock the latter toward the back of the machine. The rock shaft 168 is conveniently supported between a side wall 170 of the actuator 46 and a fixed 115 bracket 171. An arm 172 secured to the rock shaft 168 moves a link 173 rearwardly to swing an arm 174 loosely mounted on a rock shaft 175. The arm 174 (Figures 2 and 4) is provided with a pin 176, which 120 overlies the pawl 162, to swing the latter, which is secured to the rock shaft 175, into engagement with the link 151. The rock shaft may be supported by suitable brackets 177 and 178 secured to a cross-bar 180, supported by the casing 73, and is under the control of a spring 181 (Figure 4) which tends to hold the pawl 162 out of engagement 125 with the link 151. While the punctuation position of the carriage is at the printing 130

point, the cam 164 of the horizontally-disposed actuating lever may rest on one of the tappets 163, thus holding the pawl 162 in its effective locking position and preventing the actuation of the numeral keys 10. If it is desired to leave a blank space between numbers, a space bar 182 (which may be like that used in the Underwood machine) may be actuated to vibrate the dog rocker 34 of the escapement mechanism, to feed the carriage 22 one letter-space distance. The tappet 163 then rides off the cam 164, and the return spring 181 swings the pawl 162 out of engagement with the link 151, and consequently the numeral keys 10 are unlocked and also the power drive for the computing mechanism. These operations are repeated at each punctuation position. It should be understood that it is preferable to type punctuation marks in the punctuation positions by keys such as the comma key or period key; these keys being also effective to actuate the escapement mechanism in the usual way, to feed the carriage and render the numeral keys and the power drive effective.

There is also provided a cross-computing unit 183, comprising an actuator 184, and a cross-totalizer 185 adapted to travel intermittently with the typewriter carriage 22 through a computing zone, in a manner to be presently described, so that, the total, crosswise of the various columns, may also be registered, or, in other words, so that cross-computations of numbers written in the various columns may be effected. The actuator 184, of the cross-computing unit has rotatively mounted therein a master wheel 186, which may have a connection to the master wheel 55 of the column-computing unit 45 to rotate therewith. This connection may be like that disclosed in my said co-pending application No. 186,098, comprising the horizontal shaft 111 which, through the medium of bevel gears 187 and 188, is herein illustrated to drive a vertical shaft 191, which, by means of bevel gears 192 and 193, drives a horizontal shaft 194, connected through suitable gearing contained within the actuator 184, to rotate the master wheel 186 of the cross-computing unit. It will be understood that the master wheel 186 may be rotated through various angular distances, and that these rotative movements may be transferred to dial wheels 195, contained within the cross totalizer 185, through the medium of computing wheels 196 adapted to engage with the master wheel 186 seriatim, as the typewriter carriage passes through a computing zone.

The cross-totalizer 185 may be adjustably mounted on a cross-computer carriage 197 suitably guided for traveling movements in a fixed rail or guide bar 198, secured to the frame 47 of the machine.

To cause the cross-totalizer to travel intermittently with the typewriter carriage, the cross-computer carriage 197 is picked up to travel with the typewriter carriage and becomes released therefrom each time the typewriter carriage passes into and out of a computing zone, respectively. For this purpose, there may be provided a series of pick-up devices 200, which may be set on a bar 199, carried by the typewriter carriage 22, and in positions corresponding to the various columns on the work-sheet. When the carriage enters a computing zone, one of the pick-up devices 200 engages with a projection 201 on a pick-up bar 202, which forms part of a train of mechanism extending between the typewriter carriage and the cross-totalizer carriage. The pick-up bar 202 is moved to rock a bell-crank 203 about a fixed pivot 204. The bell-crank 203 is connected, by means of a link 205, to an arm 206, to move the latter and rock a shaft 207 to which said arm is secured. The rock-shaft 207 may be conveniently supported in any suitable manner, and is provided at its forward end with an upwardly-extending arm 208, which is rocked with said shaft, and is connected by means of a link 210 to the cross-computer carriage 197 (Figure 1) to move the latter with the typewriter carriage. Thus the cross-totalizer moves with the typewriter carriage step by step until the last figure is written in the column, when a pin 211 (Figure 6) on the pick-up bar 202 engages a cam 212 formed on a guide plate 213, to swing the pick-up bar about its point of connection on the bell-crank 203, and disengage the projection or pick-up hook 201 from the pick-up device 200. A return spring 214 connected to the arm 208 then becomes effective to restore the cross-computer carriage 197 with the cross-totalizer 185 and the train of mechanism, between the cross-computer carriage and the typewriter carriage, to normal position, when the pin 211 on the pick-up bar engages in the end of a slot 215, as shown in Figure 6. The typewriter carriage may then be moved to bring the next column to the computing zone, when the next pick-up device 200 engages the pick-up bar 202 to cause the cross-totalizer 185 to move with the typewriter carriage, as described for the previous column. Thus it will be seen that the cross-totalizer is caused to travel intermittently with the typewriter carriage.

It should be understood that ordinarily there is a column-totalizer provided for each column on the work-sheet, and that there is a pick-up device for each column-totalizer. It should further be understood, however, that it is sometimes desired to run the figures, being typed in a column, into the cross-totalizer without running them into a column-totalizer. In such a column there is

no need of a column-totalizer, but a pick-up device is provided to cause the cross-totalizer to move with the typewriter carriage in that column.

- 5 Ordinarily, when the cross-totalizer passes through a computing zone the numeral keys are rendered ineffective when a punctuation position is reached, and this is done by the column-totalizer (as hereinbefore described),
 10 which passes through the computing zone at the same time. When a column is reached at which there is no column-totalizer, and where computation is to be effected only in the cross-totalizer 185, the numeral keys 10
 15 may be rendered ineffective by means on the cross-computer carriage. For this purpose, there is provided a series of cams or tappets 216 arranged at the punctuation positions of the cross-totalizer 185. The tappets
 20 are herein shown as carried by a plate 217, which may be secured to the cross-computer carriage 197, so that the tappets may engage with a horizontally-disposed arm 218 on the rock shaft 168 to rock the latter as the
 25 cross-totalizer passes through the computing zone, to render the locking pawl 162 effective through the connections comprising the link 173 and arm 172 on the rock shaft, and lock the numeral keys, as herein-
 30 before described.

The cross-totalizer 185 may be adjusted on the cross-computer carriage 197, and may be located relatively to the tappets 216, by means of a scale mark 220 on the plate 217, 35 and a pointer 221 on the cross-totalizer 185. The cross-totalizer may be secured in place after adjustment by any suitable means, which may be controlled by a finger piece 222 on said totalizer.

- 40 By an inspection of Figure 2, it will be seen that the cross-computer unit 183 is located to the right and below the column-computing unit 45; and that the rock shaft 168 with the two actuating arms 167 and
 45 218 thereon, and the arm 172 to which the link 173 is connected, makes a very simple and efficient arrangement, whereby the numeral keys may be rendered ineffective by either the column-totalizers 48 or the cross-
 50 totalizer 185 at punctuation position.

A back-spacer is provided for the typewriter carriage 22 which may be like that described in the patent to Helmond No. 930,962, dated August 10, 1909, and comprises a key 223 (Figure 2), which, when depressed, swings a key lever 224, to rock a shaft 225 and a forwardly-projecting arm 226 thereon, to pull downwardly a link 227 against a suitable return spring 228. The
 55 link 227 swings a back-spacer pawl 230 into engagement with the teeth 231 of the feed rack 42; the back-spacer pawl 230 being mounted on an arm 232, which is swung about its pivot 233 until the upper end of the
 60 link 227 is arrested against the feed rack.
 65

During this movement, the pawl 230 and the arm 232 swing as an integral part. After the arm has been arrested by the feed rack, a continued movement of the link 227 causes the pawl 230 to swing about its pivot 234, 70 and against the tension of a return spring 235, thus drawing the carriage 22 back from left to right, or in other words, back-spacing the carriage through one letter-space distance. 75

Means is provided to re-connect the cross-computer carriage with the typewriter carriage, when the latter is backed into a computing zone by means of the back-spacer key. This means may be like that disclosed 80 in my co-pending application 212,213, filed January 17, 1918. For this purpose, the lever 224, when actuated by the depression of the back-spacer key 223, is caused to pull downwardly on a link 236 connected to an 85 arm 237, to rock a shaft 238; the latter having an arm 240 which moves a thrust bar 241 rightwardly, (Figure 2), so that an engaging portion 242 thereon may engage with a pin 243 on a bell-crank 244, to rock the 90 latter about a fixed pivot 245 and pull on a link 246 connected to the arm 208 of the rock shaft 207. The shaft 207 is thus rocked in a counter-clockwise direction, to move the pick-up bar 202 leftwardly through the medium of the arm 206, link 205 and bell-crank 203, until the pick-up hook re-engages the previously engaged pick-up device 200. At the same time the cross-totalizer 185 is brought into proper relation with the master wheel 186, by means of the link 210 connected to the arm 208. 95

When the typewriter carriage is out of the computing zone, the thrust bar 241 is ineffective to actuate the bell-crank 244, the thrust bar occupying such a position that the engaging portion 242 moves idly over the pin 243 on the bell-crank 244. Mechanism is provided, however, to render the thrust bar 241 effective when the carriage is moved back into a computing zone. This mechanism may include a shoe 247 (Figures 2 and 6), which is engaged by the nearest pick-up device 200, to swing a lever 248 about its fixed pivot 250 when the carriage is moved 105 back into a computing zone. The lever 248 has pivotally mounted thereon at 251 an intermediate lever 252 which engages under bent-off portion 253 (Figure 6) of the pick-up bar 202. As the lever 248 is swung about its pivot 250, the intermediate lever 252 swings about the bent-off portion 253 as a fulcrum, to pull upwardly on a link 254, and through a yielding connection, comprising a spring 255, swing a lever 256 about its 110 fulcrum 257, to cause the forward end thereof, which projects into a slot 258 of thrust bar 241, to lower the thrust bar and bring the engaging portion 242 into co-operative 120 relation with the pin 243 on the bell-crank 125 130

244. A lip 260 (Figure 2) on the pick-up bar 202 may engage in a slot 261 of the bracket or guide plate 213, to prevent lifting of the pick-up bar 202 while the intermediate lever 252 is being actuated. If the back-space key is now actuated, the thrust bar will actuate the bell-crank 244 to reconnect the cross-computer carriage by means of the pick-up bar, as previously described.
- 10 The bent-off portion 253 on the pick-up bar, during the re-connecting movement of the latter, moves out of engagement with the intermediate lever 252, but before this takes place, a lip 262 on the thrust bar engages under a fixed pin 263 to retain the effective relation between the engaging portion of the thrust bar and the pin 243 on the bell-crank 244.
- 15 Provision is made to render the numeral keys 10 ineffective by locking them and also the motor-release against actuation when the typewriter carriage is backed into a computing zone, without the aid of the back-spacer key, so as to avoid typing of numbers and computing the same, until the back-spacer key has been actuated to re-connect the cross-computer carriage and re-position it relatively to the typewriter carriage. To do this, the lever 256 is provided with a pin 264, engaging with an arm 265 on the shaft 175, to rock the latter and swing the pawl 162 into effective holding relation with the link 151, thus locking the motor-release shaft 76, and consequently rendering the numeral keys and the computing mechanism ineffective. It will be understood that when the locking of the keys takes place, the thrust bar 241, connected with the back-spacer key, is also lowered to its effective position.
- 20 To release the pawl 162 and thus unlock the numeral keys and the motor-release, the back-spacer key 223 is actuated to re-connect the cross-computer carriage 197 with the typewriter carriage 22, as previously described, during which time the thrust bar is held in its effective relation with the pin 243 on the bell-crank 244 by means of the pin 263, and consequently the pawl 162 is held in its locking position after the bent-off portion 253 of the pick-up bar moves away from the intermediate lever 252. As soon as the lip or bent-off portion 262 is disengaged from the pin 263 on the return stroke of the thrust bar 241, a spring 266, connected to the intermediate lever 252 (Figure 6), restores the link 254 and the thrust-bar-controlling lever 256 to their normal positions, at which time the rear end of the lever 256 is lowered with the pin 264 and permits the spring 181 to rock the shaft 175, to withdraw the pawl 162 from effective relation with the link 151, and consequently unlock the motor-release, so that the computing mechanism and the numeral keys may be actuated.

Provision is made to prevent accidental simultaneous depression of two keys, which would otherwise result in both keys becoming connected with the power drive and the jamming of the type-bars near the printing point. This means also prevents the actuation of another key, before a previously actuated key returns sufficiently to become disconnected from the universal bar under the control of the power drive. To accomplish the above, each numeral key 10 is provided with a pendant 267 (Figures 1 and 3), and each pendant has a wedge 268 thereon, which, when the numeral key is actuated, is forced between two depending pawls 270. These pawls are arranged in pairs which form a series or group, which are pivotally mounted at 271 (Figure 3) on a plate 272, and are located between two studs 273 and 274 at the ends of the group 85 of pawls. Sufficient space is left in the group of pawls to permit the intrusion of a single wedge at a time, so that when one numeral key is active, the other numeral keys are locked against actuation, as the 90 pawls are jammed tight together and prevent the intrusion of the wedges 268.

To rapidly position the typewriter carriage denominationally in any one of the various columns, there is provided a decimal tabulator which may be like that used in the Underwood addendagraph. The tabulator comprises tabulator keys 275, which, when depressed, swing key levers 276 about their fulcrum 277, to raise plungers 278 100 against the tension of return springs 280, to project denominational stops 281 at the upper ends of said plungers 278, into the path of column stops 282. The column stops 282, as herein shown, are of the usual key-set type and are settable in columnar positions on a stop bar 283 secured to the typewriter carriage 22. When any one of the plungers 278 is raised, it engages with a universal bar 284, to rock a shaft 285, 110 and pull downwardly on a link 286, to swing a lever 287 about its pivot 288, and raise the carriage feed rack 42 out of mesh with the pinion 43, thus releasing the carriage 22 and permitting it to be drawn leftwardly by the spring drum 25 until it is arrested, in the selected position, by the column stop 282 which strikes the actuated denominational stop 281.

It is desirable to prevent the release of 120 the power-drive or the actuation of the numeral keys during a tabulating operation, or, in other words, while a tabulating key is in its actuated position. For this purpose there is provided a universal bar 125 290, which overlies the tabulator key levers 276 at their rear ends, so that it may be actuated by any one of the tabulator key levers. The universal bar forms part of a lever 291, which, when actuated, swings 130

about the fulcrum 277 and engages at its forward end, by means of pin-and-slot connection 292, with an intruding dog or wedge 293, to swing the latter about its fixed pivot 294 and cause it to enter between two of the pawls 270 (Figures 1 and 3), thus taking up the space between the two studs 273 and 274 and leaving no space for the intrusion of the wedges on the numeral keys, thus locking the numeral keys against actuation, and consequently preventing the release of the power-drive, which, it will be remembered, is under the control of the numeral keys.

15 From the foregoing it will be understood that the key-locking means including the pawls 270 is common to both the numeral keys and the tabulator keys, and that any one of the keys in either set is locked against 20 actuation when a key of the other set is active. As a result of this, the power-drive cannot be released, and consequently a computation cannot take place when a tabulator key is active, thus insuring that the carriage 25 is brought to rest and a computing wheel into exact register with the master wheel, after a tabulating operation, and before the computing mechanism can be actuated, to run the number into the 30 totalizer.

The platen 20 may be shifted from lower to upper-case position, so as to enable printing with the upper-case types 295 on the type bars 17. For this purpose, there is provided a case-shift key 296, which, when depressed, swings a lever 297 and an arm 298 thereon about the fulcrum rod 13, the arm being effective to swing a shift frame 300 about its pivot 301. The shift frame comprises a rail or bar 302, which is moved upwardly to shift the platen frame 21 by means of a roller 303 secured to said frame, said roller traveling back and forth on said shift rail 302 during the traveling movements of 40 said carriage. The platen may be guided in its case-shifting movements by arms 304 projecting forwardly from a rock shaft 305 on the carriage frame 22.

It is desirable at times to render the computing mechanism ineffective so as to enable 50 the typing of numbers in columns without computing the same. For this purpose, there is provided a non-compute key 306, which may be swung forwardly about a pivot 307, to pull a link 308 connected thereto, and swing a lever 310 pivotally mounted at 311 on the case-shift frame 300. The lever 310 is connected at its lower end to a rearwardly-extending link 312, to rock a bell-crank 313, 55 pivotally mounted on the motor release shaft 76, in a counter-clockwise direction. The bell-crank 313 engages with a pin 314 on the actuating arm 78, to swing the latter about its pivot 315, to take the tooth 80 thereon out 60 of effective relation with the tooth 81 on the

holding pawl 62. The bell crank 313 is pivotally mounted on the shaft 76, so that it and the rock shaft 76 may be actuated independently of each other. Any suitable form of detent may be used with the key 306 to hold the actuating element 78 indefinitely out of action.

From the foregoing, it will be understood if a numeral key 10 is actuated while the actuating arm 78 is out of action, the power-drive will not be released, and consequently there will be no computing action. It will further be understood that, although there is no computation performed when a totalizer passes through a computing zone, while the arm 78 is out of action, the totalizer still serves to lock the keys and the power-drive when a punctuation position is reached.

Variations may be resorted to within the scope of the invention, and portions of the improvements may be used without others.

Having thus described my invention, I claim:

1. In a combined typewriting and computing machine, the combination of a carriage, a totalizer to travel with said carriage, numeral keys, a rock-shaft, tappets on said totalizer, means to be engaged by said tappets to rock said shaft, and means, including a latch controlled by said rock-shaft, to prevent writing numbers at predetermined positions in the travel of said carriage.

2. In a combined typewriting and computing machine, the combination of a carriage, a totalizer to travel with said carriage, 100 numeral keys, a rock-shaft, tappets on said totalizer, a lever to be engaged by said tappets to rock said shaft, and key-locking means connected with said rock-shaft to prevent writing numbers at a predetermined position in the travel of said totalizer.

3. In a combined typewriting and computing machine, the combination of a carriage, a totalizer to travel with said carriage, numeral keys, a carriage escapement, a horizontally disposed rock-shaft, tappets on said totalizer, a horizontally disposed pivoted lever to be engaged by said tappets, a vertical arm on said rock-shaft to be engaged by said lever, key-locking means connected with 115 said rock-shaft, and a punctuation type key to actuate said carriage escapement when said numeral keys are locked.

4. In a combined typewriting and computing machine, the combination of a carriage; 120 a totalizer to travel with said carriage; tappets on said totalizer; an actuator for said totalizer; numeral keys; and means to prevent the actuation of said numeral keys at predetermined positions in the travel of said totalizer; said means comprising a horizontally disposed lever pivotally mounted at said actuator, and extending crosswise thereof, a vertically pivoted lever, at one side of said actuator, with which said horizontally 125

disposed lever engages, and locking mechanism connected with said vertically pivoted lever.

5. In a combined typewriting and computing machine, the combination of a carriage; a totalizer to travel with said carriage; numeral keys; and means to lock said keys; said means comprising an element actuatable by all of said numeral keys, a pawl to co-operate with said element, a spring to normally hold said pawl out of effective relation with said element, and a connection actuatable by said carriage to render said pawl effective at predetermined positions in the travel of said carriage.

6. In a combined typewriting and computing machine, the combination of a carriage, a totalizer to travel intermittently with said carriage, numeral keys, means to prevent the writing of numbers by the numeral keys, and means whereby said preventing means will be rendered effective at predetermined positions in the path of said totalizer as the latter travels relatively to said preventing means.

7. In a combined typewriting and computing machine, the combination of a main carriage, a sub-carriage to travel intermittently with said main carriage, numeral keys, a totalizer on said sub-carriage, a device on said sub-carriage, and means actuatable by said device to prevent writing numbers at a predetermined position in the travel of said sub-carriage.

35 8. In a combined typewriting and computing machine, the combination of a carriage, a cross-totalizer to travel intermittently with said carriage, numeral keys, a carriage escapement, means to lock said numeral keys, means for rendering said locking means effective at predetermined positions in the travel of said totalizer relative thereto, and key-operated means to actuate said carriage escapement when said numeral keys are locked.

9. In a combined typewriting and computing machine, the combination of a main carriage, a sub-carriage to travel intermittently with said main carriage, numeral keys, a plurality of cams on said sub-carriage, a totalizer detachably mounted on said sub-carriage and adjustable relatively to said cams, and means actuatable by said cams to lock said numeral keys at positions in the travel of said totalizer corresponding to the positions of said cams.

10. In a combined typewriting and computing machine, the combination of a main carriage which may carry a work-sheet with one or more columns thereon, and which is adapted to pass through a computing zone, a sub-carriage to travel intermittently with said main carriage through the computing zone, number-printing devices to print at a

common printing point, a totalizer on said sub-carriage, a plurality of cams on said sub-carriage, and means actuatable by said cams, when a punctuation position of any one of the columns is brought to the printing point, to lock said printing devices.

11. In a combined typewriting and computing machine, the combination of a carriage, a column-totalizer to travel with said carriage, a cross-totalizer to travel intermittently with said carriage, numeral keys, and means actuatable by either of said totalizers to prevent writing numbers at predetermined positions in the travel of said totalizers.

12. In a combined typewriting and computing machine, the combination of a main carriage, a totalizer on said carriage, a sub-carriage to travel intermittently with said main carriage, a totalizer on said sub-carriage, numeral keys, tappets for each totalizer, a rock-shaft actuatable by the tappets of either totalizer, and numeral - key - locking means connected with said rock-shaft.

13. In a combined typewriting and computing machine, the combination of numeral keys; a main carriage; a sub-carriage to travel intermittently with said main carriage; a column-computing unit comprising two elements, namely, an actuator and a totalizer, one of said elements being adapted to travel with said main carriage; a cross-computing unit comprising two elements, namely, an actuator and a totalizer, one of said elements being adapted to travel with said sub-carriage; numeral keys; a rock-shaft extending from the relatively fixed element of one computing unit, to the like element of the other computing unit; a device on the main carriage; an arm on said shaft; an intermediate member actuatable by said device, to rock said shaft; a device on the sub-carriage to rock said shaft; and locking means for said numeral keys connected to said rock-shaft.

14. In a combined typewriting and computing machine, the combination of numeral keys; a main carriage, a sub-carriage; a column-computing unit comprising an actuator, and a totalizer to travel with said main carriage; a cross-computing unit comprising an actuator, and a totalizer to travel with said sub-carriage; the actuator of said cross-computing unit being located to one side of the other actuator; numeral keys; a horizontally disposed rock-shaft extending from one actuator to the other; a vertically disposed arm on said rock-shaft at the first-mentioned actuator; cams on the first-mentioned totalizer; an intermediate member actuatable by said cams; said member engaging with the arm on said rock-shaft to actuate the latter; a horizontally disposed arm on said rock-shaft; cams for the second-mentioned totalizer to engage with said last-

- mentioned arm to actuate said rock-shaft; and key-locking means connected to said rock-shaft.
15. In a combined typewriting and computing machine, the combination of computing mechanism, a totalizer, numeral keys, actuating mechanism for said computing mechanism under the control of said numeral keys, a universal bar associated with the actuating mechanism, key-locking means associated with said universal bar, and means actuatable by said totalizer to render the locking means effective as the totalizer travels relatively to said key-locking means.
16. The combination of a carriage, numeral keys, computing mechanism, normally held power driving means for said computing mechanism, releasing means for said driving means, said releasing means being under the control of said keys, and means to lock said releasing means and thereby said numeral keys against actuation at predetermined positions in the travel of said carriage.
17. In a combined typewriting and computing machine, the combination of a carriage; a computer carriage to travel intermittently with said carriage; numeral keys; and means to lock said numeral keys; said means comprising a member actuatable by said keys, a co-operative element, means to hold said co-operative element out of engagement with said member, and means actuatable by said computer carriage at predetermined positions in its travel to bring said co-operative element into engagement with said member to lock the latter and prevent the actuation of said keys at predetermined positions in the travel of said carriage.
18. The combination of a main carriage, a sub-carriage to travel with said main carriage through a zone, printing devices including keys, normally held driving means associated with said printing devices, releasing means for said driving means, means to release said sub-carriage so that it may resume its normal position when the main carriage passes out of the zone, means associated with the releasing means for said driving means, to render said printing devices ineffective when the main carriage is backed into the computing zone, key-actuated means to reconnect the sub-carriage with the main carriage, and means to render said keys effective when the sub-carriage is reconnected.
19. In a combined typewriting and computing machine, the combination of a main carriage, computing mechanism, a computer carriage to travel intermittently with said main carriage through a computing zone, numeral keys, normally held driving means for said computing mechanism, releasing means for said driving means, means to release
- lease said computer carriage so that it may resume its normal position when the main carriage passes out of the computing zone, means associated with the releasing means for said driving means, to render said numeral keys ineffective when the main carriage is backed into the computing zone, key-actuated means to reconnect the computer carriage with the main carriage, and means to render said keys effective when the computer carriage is reconnected.
20. In a combined typewriting and computing machine, the combination of a carriage, computing mechanism, numeral keys, normally held actuating mechanism for said computing mechanism, under the control of said keys, a carriage escapement, releasing means for said actuating mechanism, said releasing means being under the control of said numeral keys, means to lock said escapement to hold said carriage, means comprising a member connected with said releasing means, to render the escapement locking means effective, locking means to co-operate with said member, and means actuatable by said carriage to render said last-mentioned locking means effective.
21. In a combined typewriting and computing machine, the combination of a carriage, computing mechanism, numeral keys, actuating mechanism for said computing mechanism under the control of said keys, a carriage escapement, a universal element actuatable by said keys, means to lock said escapement to hold said carriage, means comprising a member connected with said universal element to render the escapement locking means effective, locking means to co-operate with said member, and means actuatable by said carriage to render said last-mentioned locking means effective.
22. In a combined typewriting and computing machine, the combination of a carriage, computing mechanism, a totalizer, tappets on said totalizer, numeral keys, actuating mechanism for said computing mechanism under the control of said keys, a carriage escapement, a universal bar actuatable by said keys, means to lock said escapement to hold said carriage, means comprising a member connected with said universal bar to render the escapement locking means effective, locking means comprising a pawl to co-operate with said member, and means actuatable by the tappets on said totalizer to render said pawl effective to hold said universal bar.
23. In a combined typewriting and computing machine, the combination of a carriage, numeral keys, computing mechanism, a power drive under the control of said numeral keys and with which said keys may become connected, means to prevent the simultaneous actuation and connection of two

keys with said power drive, and locking means to lock said power drive to prevent the actuation of any one of said keys at punctuation positions in the travel of said carriage.

24. In a combined typewriting and computing machine, the combination of a carriage, a totalizer to travel with said carriage, numeral keys, computing mechanism, a power drive for said computing mechanism and under the control of said numeral keys, means associated with said numeral keys to prevent simultaneous actuation of two of said keys, and means to lock said power drive to prevent a computing action and the actuation of any one of said keys at punctuation positions in the travel of said totalizer.

25. In a combined typewriting and computing machine, the combination of a carriage, numeral keys, computing mechanism, a power drive for said computing mechanism, and with which said numeral keys may become connected, and means to prevent the simultaneous connection of two keys with said power drive.

26. In a combined typewriting and computing machine, the combination of a carriage, numeral keys, computing mechanism, means to prevent simultaneous actuation of two keys, normally held power driving means, releasing means for said power driving means under the control of said keys, and means to lock said releasing means, and thereby said keys, to render said power driving means ineffective at punctuation positions of said carriage.

27. The combination of a carriage, numeral keys, computing mechanism, a normally held power drive for said computing mechanism, releasing means for said power drive under the control of said numeral keys, tabulating mechanism for said carriage, said tabulating mechanism comprising keys, and means to prevent the release of said power drive by any one of said numeral keys when a tabulator key is active.

28. The combination of a carriage, numeral keys, computing mechanism, a normally held power drive for said computing mechanism, releasing means for said power drive under the control of said numeral keys, tabulating mechanism for said carriage, said tabulating mechanism comprising keys, and means to prevent the actuation of the tabulator keys while the power drive is active.

29. In a combined typewriting and computing machine, the combination of numeral keys, computing mechanism, a power drive, releasing means for said power drive actuatable by said keys, tabulating mechanism comprising keys, and means to lock said numeral keys to prevent the release of said power drive when a tabulator key is active.

65 30. The combination of a carriage, a se-

ries of numeral keys, computing mechanism, a normally held power drive for said computing mechanism, releasing means for said power drive under the control of said numeral keys, tabulating mechanism for said carriage, said tabulating mechanism comprising a series of keys, and means common to both series of keys to prevent the actuation of any one of the keys in one series, when a key of the other series is active.

70 31. The combination of a carriage, numeral keys, computing mechanism, a normally held power drive for said computing mechanism, a release for said power drive under the control of said numeral keys, tabulator keys, a carriage release under the control of said tabulator keys, and means to lock said tabulator keys to prevent the release of said carriage when the power drive is active.

80 32. The combination of a carriage, numeral keys, computing mechanism, a normally held power drive for said computing mechanism, a release for said power drive under the control of said numeral keys, tabulator keys, a carriage release under the control of said tabulator keys, and means to lock said numeral keys to prevent the release of said power drive while said carriage is released by one of said tabulator keys.

85 33. The combination of a carriage, numeral keys, computing mechanism, a normally held power drive for said computing mechanism, a release for said power drive under the control of said numeral keys, tabulator keys, a carriage release under the control of said tabulator keys, and means to permit the actuation of only one release at a time.

90 34. The combination of a carriage, numeral keys, computing mechanism, a normally held power drive for said computing mechanism, a release for said power drive under the control of said numeral keys, tabulator keys, a carriage release under the control of said tabulator keys, and means common to the numeral keys and the tabulator keys to permit the actuation of only one release at a time.

95 35. In a combined typewriting and computing machine, the combination of numeral keys, computing mechanism, a power drive, releasing means for said power drive actuatable by said keys, means whereby any one of said keys may be actuated by said power drive after the latter is released, and means to prevent the actuation of another key before the actuated key has become disconnected from said power drive on the return of said key to normal position.

100 36. The combination of a carriage, type keys, a normally held power drive for said type keys, a release for said power drive under the control of said type keys, a tabulator for said carriage, said tabulator com-

prising keys, and means to prevent the release of said power drive by any one of said type keys when a tabulator key is active.

37. The combination of a carriage, type keys, a normally held power drive for said type keys, a release for said power drive under the control of said type keys, a tabulator for said carriage, said tabulator comprising keys, and means to prevent the actuation of the tabulator keys while the power drive is active.

38. The combination of a carriage, type keys, a normally held power drive for said type keys, a release for said power drive under the control of said type keys, a tabulator for said carriage, said tabulator comprising keys, and means common to the type keys and the tabulator keys to prevent the actuation of any one of the keys in one series 20 of keys when a key of the other series is active.

39. The combination of a carriage, printing devices, a normally held power drive for said printing devices, a release for said power drive under the control of said printing devices, tabulator keys, a carriage release under the control of said tabulator keys, and means to lock said tabulator keys to prevent the release of said carriage when 30 the power drive is active.

40. The combination of a carriage, printing devices, a normally held power drive for said printing devices, a release for said power drive under the control of said printing devices, tabulator keys, a carriage release under the control of said tabulator keys, and means to lock said printing devices to prevent the release of said power drive while said carriage is released by one 40 of said tabulator keys.

41. The combination of a carriage, printing devices, a normally held power drive for said printing devices, a release for said power drive under the control of said printing devices, tabulator keys, a carriage release under the control of said tabulator keys, and means to permit the actuation of only one release at a time.

42. The combination of printing devices 50 including keys, a power drive, releasing means for said power drive under the control of said keys, actuating means to which any one of said keys may be connected, so that it may be actuated by said power drive 55 after the latter is released, and means to prevent the actuation of another key before an actuated key has become disconnected from said actuating means.

43. The combination with a carriage, com- 60 puting mechanism, a plurality of totalizers to travel with said carriage, and a cross-totalizer to travel intermittently with said carriage, of numeral keys, a normally held power drive, releasing means for said power drive, locking means for said numeral keys,

said locking means being associated with the power drive releasing means, back-spacing means to reverse said carriage, means including a member to render said locking means effective when the carriage is reversed 70 without the aid of the back-spacing means, a normally ineffective connection from said back-spacing means whereby the cross-totalizer may be repositioned relatively to the carriage, and means controlled by said member to render said connection effective. 75

44. The combination of a carriage, numeral keys, computing mechanism, a power drive, a universal bar actuatable by said keys, locking means for said universal bar, means 80 on said carriage, means actuatable by the means on said carriage to render said locking means effective, a power drive for said computing mechanism, holding means for said power drive, a releasing member for 85 said holding means, said member being connected with said universal bar, and means to render said universal bar ineffective, to release said power drive without affecting 90 the locking means for said universal bar, when it is desired to type numbers without computing them.

45. In combination, a carriage, manually operable printing devices, means to prevent the actuation of more than one of said printing devices at one time, a power drive, means whereby the initial movement of any one of said printing devices will render said power drive effective, tabulator keys, a carriage release under the control of said tabulator keys, and means acting through said preventing means to lock the tabulator keys to prevent the release of the carriage when the power drive is active.

46. In a combined typewriting and computing machine, in combination, a carriage, a totalizer to travel therewith, numeral keys, means to lock said keys, comprising an element actuatable by all of said keys and a latch 100 to co-operate with said element and prevent movement thereof, means normally urging said latch out of effective relation with said element, and a connection actuatable by said carriage to render said latch effective at predetermined positions in the travel of said carriage.

47. In a combined typewriting and computing machine, in combination, a main carriage, a sub-carriage to travel intermittently 110 with said main carriage, numeral keys, a numeral-key lock, a totalizer on said sub-carriage and adjustable therealong, and co-operating cam-devices on said sub-carriage and said lock to render the latter effective 115 when the totalizer is in punctuation position.

48. In a combined typewriting and computing machine, in combination, a main carriage, means to determine one or more com- 120

puting zones therefor, a sub-carriage to travel intermittently with said main carriage while passing through computing zones, number-printing devices effective at a common printing point, a totalizer on said sub-carriage, number - printing - device - locking means, and means, including cams on said sub-carriage and locking means, whereby the latter will be rendered effective at punctuation positions in the computing zones.

49. In a combined typewriting and computing machine, in combination, a carriage, numeral keys, computing mechanism, power-driving means, means including a numeral-key-controlled member for rendering said driving means effective, and means, rendered effective at punctuation positions of the carriage, to lock said member and thereby said keys.

50. In a combined typewriting and computing machine, in combination, a carriage, numeral keys, computing mechanism, power-driving means for said computing mechanism, including a numeral-key-controlled member for rendering said driving means effective, tabulating mechanism for said carriage, including keys for actuating the same, and means whereby a tabulating key, when actuated, will prevent actuation of said numeral-key-controlled member by said numeral keys.

51. In combination, a carriage, numeral keys, computing mechanism, a power-drive for said computing mechanism, means including a numeral-key-controlled member for rendering said drive effective, tabulating mechanism for said carriage, comprising keys to actuate the same, and means to prevent actuation of the tabulating keys when the power-drive is active.

52. In combination, numeral keys, com-

puting mechanism, a power-drive including a numeral-key-controlled member for rendering said drive effective, tabulating mechanism comprising keys for actuating the same, and means to lock said numeral keys to prevent actuation of said member when a tabulating key is active.

53. In combination, a carriage, numeral keys, computing mechanism, a power-drive, means including a device actuatable by said numeral keys for rendering said drive effective, tabulator keys, a carriage-release under the control of said tabulating keys, and means to lock said tabulator keys to prevent release of the carriage thereby when the power-drive is active.

54. In combination, a carriage, numeral keys, computing mechanism, a power-drive for said computing mechanism, means including a numeral-key-controlled member for rendering said drive effective, tabulator keys, a carriage-release under the control of said tabulator keys, and means to lock said numeral keys and thereby prevent actuation of said key-controlled member while the carriage is released by one of the tabulator keys.

55. In combination, a carriage, a set of type-keys, a power-drive for said type-keys, means including a key-controlled member for rendering said power-drive effective, a tabulator for said carriage, including a set of keys for actuating the same, and means, common to the type-keys and the tabulator keys, to prevent the actuation of any one of the keys in one set of keys when a key of the other set is active.

HENRY L. PITMAN.
